Att'y.

UNITED STATES PATENT OFFICE

ELMER G. GARTIN, OF CLAREMONT, NEW HAMPSHIRE, ASSIGNOR TO SULLIVAN MACHINERY COMPANY, A CORPORATION OF MASSACHUSETTS

DRILLING MECHANISM

Application filed March 24, 1927. Serial No. 178,109.

This invention relates to drilling mechanisms and more particularly appertains to rock drilling mechanisms of the pressure fluid actuated hammer type.

5 An object of this invention is to provide an improved rock drill. Another object is to provide an improved rock drill having an improved and simplified supporting means for the cleansing fluid conducting tube and 10 for a rotatable element of the drill steel rotation mechanism, said supporting means cooperating with the rear motor head to form a lubricant reservoir. Another object is to provide an improved supplemental head 15 member clamped between the rear motor head and the ratchet ring of the rotation mechanism and having a central boss projecting through the back head for supporting the cleansing fluid supply tube, the pawl car- 20 rier of the rotation mechanism being journaled in said supplemental head. Another object is to provide an improved structure exceedingly rugged and compact and which may be manufactured at a minimum of ex- 25 pense. These and other objects will, however, hereinafter more fully appear.

In the accompanying drawing I have shown for purposes of illustration one form which the invention may assume in practice.

30 In this drawing,—

Fig. 1 is a central longitudinally extending vertical sectional view through a rock drill embodying the improved construction, parts being shown in elevation to simplify 35 illustration.

Fig. 2 is a rear end elevational view of the rock drill shown in Fig. 1.

In this illustrative embodiment of the invention there is shown a rock drill generally 40 designated 1 of the pressure fluid actuated hammer type and comprising a cylinder 2 having a bore 3 in which a hammer piston 4 is reciprocably mounted. The hammer piston 4 is provided with a forwardly project- 45 ing striking bar 5 extending through a central bore 6 formed within a front buffer ring or head member 7. As the piston 4 is reciprocated within the bore 3 under the action of pressure fluid admitted to the cylinder 50 under the control of a usual automatic valve

mechanism 8, the striking bar delivers a series of impacts to the shank of a hollow drill steel 9 loosely mounted within the forward end of the drill. As illustrated, the rear end of the cylinder bore is closed by a 55 perforated disc or washer 10 seated within a counterbore 11 formed within the rear end of the cylinder. The washer 10 is also seated in a counterbore 12 formed within a rear- 60 wardly located ratchet ring 13. In accord- 65 ance with this illustrative embodiment of the invention there is shown interposed between the ratchet ring 13 and a rear head 14 a supplemental head member 15 having pro- 70 jecting cylindrical portions 16 and 17 formed 75 on its opposite faces and respectively pro- 80 jecting within suitable bores formed within the back head and ratchet ring as clearly shown in Fig. 1. The member 15 has formed integral therewith a central boss 18 project- 85 ing rearwardly therefrom through an open- 90 ing 19 formed centrally within the rear head 14. The boss 18 projects beyond the head 14 and is externally threaded at 19a to receive a nut 20. It is obvious that when the nut 20 is suitably tightened, the head member 15 and rear head 14 are rigidly clamped together and when positioned in this manner the heads cooperate to form a lubricant res- 95 ervoir 21. The rear head 14 carries a usual throttle valve mechanism 22 which is adapt- 100 ed to control the flow of pressure fluid from a suitable supply connection 23 to the automatic valve mechanism 8 in a well known manner.

In this instance the ratchet ring 13 has housed therein a pawl carrier 24 which carries a plurality of spring-pressed pawls which cooperate with internal teeth 25 within the ratchet ring 13 in a well known manner. As 90 shown, the pawl carrier has projecting from the rear surface thereof a cylindrical bearing portion 26 which is rotatably mounted within a bore 27 formed within the supplemental head member 15. The pawl carrier 24 also has projecting forwardly therefrom a spirally grooved rotation bar 28, the spiral grooves of which cooperate with spiral vanes herein formed integral with a rotation nut 29 threadedly connected at 30 within the rear 105 110

end of the piston 4. The striking bar 5 of the piston has formed on the periphery thereof longitudinally extending straight grooves or flutes 31 which cooperate with straight vanes 32 formed on a chuck nut 33 threadedly connected at 34 within a chuck sleeve 35. The chuck sleeve 35 is rotatably mounted within a chuck housing 36 and herein carries a chuck bushing 37 within which the drill steel 9 is mounted. The chuck housing 36, the buffer ring 7, the cylinder 2, the ratchet ring 13, supplemental head 15 and rear head 14 are held in operative assembled relation by means of usual side bolts 38. It is accordingly evident that as the piston 4 moves forwardly within the cylinder bore 3, the spiral grooves on the rotation nut 29 which cooperate with the spirally grooved rotation bar effect rotation of the latter, the pawls slipping over the ratchet teeth 25 and the piston striking an unimpeded blow on the shank of the drill steel 9. Upon reversal of the hammer piston the pawls of the ratchet mechanism engage the ratchet teeth 25 and consequently rotation of the bar 28 is prevented. It is accordingly evident that as the piston moves rearwardly, the spiral grooves on the then stationary rotation bar impart a turning movement to the piston which is transmitted by the grooves in the striking bar, the chuck nut 33, the chuck sleeve 35, the chuck bushing 37 to the drill steel 9. It is therefore evident that the drill steel is given a slight turning movement upon each reciprocation of the hammer piston.

In this improved construction it will be observed that the boss 18 on the supplemental head 15 is centrally bored at 39, the rotation bar 28 is centrally bored at 40, and the striking bar 5 centrally bored at 41 and extending through these bores forwardly within the hollow drill steel 9 is a cleansing fluid conducting tube 42, the tube extending rearwardly beyond the boss 18 and having formed on its rear end a radial flange 43. As shown, surrounding the rear end of the tube 42 and disposed within a bore 44 within the rear end of the central boss 18 is a compressible packing washer 45, the nut 20 when tightened clamping the flange 43 of the cleansing tube 42 between the nut and the washer 45, compressing the latter, thereby preventing leakage of fluid past the packing and through the bore 39 to the rotation parts. Water under pressure is adapted to be supplied to the cleansing tube 42 through a port 46 formed in the rear head 14 and communicating through a passage 47 in the nut 20 with the tube. When the throttle valve mechanism is suitably manipulated, pressure is supplied to the automatic valve mechanism 8 and suitably distributed to the cylinder bore to effect reciprocation of the piston in the usual manner. Simultaneously, pressure fluid is admitted from the cylinder bore through suitable restricted passages 48 in the washer 10 to the

oil reservoir 21, the pressure fluid acting on the oil within this reservoir and forcing the same through a suitable automatic valve mechanism 49 carried by the supplemental head 15 and controlled by the fluctuating pressure within the rear end of the cylinder bore, to the parts of the rotation mechanism and thence to the motor. From the foregoing, it is thought that the construction, operation, and many advantages of the herein described invention will be apparent to those skilled in this art, without further description. 70 75

As a result of this invention it will be noted that an improved supporting structure is provided for the water tube and this supporting structure also forms a support within which the pawl carrier of the rotation mechanism is journaled. It will also be noted that the improved supplemental head structure cooperates in an improved manner with the rear head to form a lubricant reservoir, the lubricant being transmitted through a supplemental head to the rotation parts and the motor cylinder. Furthermore the improved water tube support and securing means are readily accessible, it being possible to remove the water tube by simply unthreading the nut and withdrawing the tube longitudinally from the machine, thereby permitting expeditious and facile replacement of the latter. These and other advantages of the improved construction will be readily apparent to those skilled in this art. 80 85 90 95

While I have in this application specifically described one form which my invention may assume in practice, it will be understood that this form of the same is shown for purposes of illustration and that the invention may be modified and embodied in various other forms without departing from its spirit or the scope of the appended claims. 100 105

What I claim as new and desire to secure by Letters Patent is:

1. In a drilling mechanism, a motor comprising a cylinder and a piston reciprocable therein, a rear head for said cylinder having a central bore and a recess, a cooperating supplemental head having a central rearwardly projecting boss extending through said bore, said latter head also having a recess, means connectible to said boss for clamping said heads directly together with the recesses in said heads cooperating to form a lubricant reservoir, and means for securing said heads to said cylinder. 110 115 120

2. In a drilling mechanism, a motor comprising a cylinder and piston reciprocable therein, a rear head having a central bore therein, a cooperating intermediate head between the cylinder and said rear head and having a central boss projecting rearwardly through said bore, said heads having cooperating means forming an annular fluid containing chamber therebetween from which 125 130

fluid is supplied to parts of the motor, means connectible to said boss and engaging said rear head for clamping said heads directly together, and means for securing said heads to the cylinder.

5 3. In a drilling mechanism, the combination specified in claim 2 wherein there is further provided a cleansing fluid tube extending centrally through the motor and longitudinally through and supported by said boss.

10 4. In a drilling mechanism, a motor comprising a cylinder and piston reciprocable therein, a rear head having a central bore therein, a cooperating intermediate head between the cylinder and said rear head and having a central bore projecting rearwardly through said bore, each of said heads having cooperating annular recesses forming an annular fluid containing chamber between the heads from which fluid is supplied to parts of the motor, a cleansing fluid tube extending through and supported by said boss, a cap threaded on the end of said boss and engaging 20 said rear head for clamping the heads directly together, means provided by said cap for holding said cleansing fluid tube in position, and means for securing said heads to said cylinder.

25 5. In a drilling mechanism, a motor comprising a cylinder and a piston, a rear head for said cylinder having a central bore, a cooperating supplemental head having a central rearwardly projecting boss extending 30 into said bore, said heads having cooperating means forming a lubricant reservoir, means connectible to said boss and engaging said supplemental head for securing said heads directly together, and means for securing 35 said heads to said motor cylinder.

In testimony whereof I affix my signature.
ELMER G. GARTIN.
